AUTOMATIC LEVELING SYSTEM FOR ELEVATORS

James H. Bartholomew, Warsaw, N. Y.

Application October 10, 1936, Serial No. 105,070

19 Claims. (Cl. 187—29)

The present invention relates to an automatic leveling system for elevator cars and more particularly to an electro-mechanical type of automatic leveling system.

5 Although automatic leveling systems for elevators are known, the present practice is to employ controls which are fully electrical and which include complicated and expensive electrical equipment and circuits and which are comparatively expensive to install and maintain.

10 The primary object of the present invention is the provision of an electro-mechanical automatic leveling system for elevators which is simple in construction and essentially mechanical in operation.

15 Another object of the invention is an electro-mechanical leveling system for an elevator car adapted to be leveled with respect to a plurality of floors or landings, which is mechanically and easily adjusted and which is economically maintained.

20 A further object is the provision of a leveling relay corresponding to each floor of the elevator hatchway, which is operative only when the elevator car is adjacent the respective floor and which is mechanically controlled by the position of the elevator car with respect to said floor.

25 Still another object of the invention is the provision of a leveling relay including a pair of control contacts, an armature carrying one of said contacts, a magnetic coil for attracting said armature, and a contact arm carrying the other of said contacts and moved to open the same when the elevator car is level with the floor even though said magnetic coil is still energized.

30 Other and further objects of the invention will be suggested to those skilled in the art by the accompanying disclosure.

35 To attain the said above and other objects, the invention consists in certain improvements and combinations of parts all as fully set forth in the following specification and defined in the appended claims.

40 Reference is hereby made to the accompanying drawings wherein like reference characters designate similar elements and wherein:

45 Fig. 1 is a complete diagrammatic illustration of the invention including the essential mechanical members as well as the necessary electrical circuits.

50 Fig. 2 is a side elevation of the leveling relay and limit arms for one floor and showing the relay in inoperative condition.

55 Fig. 3 is a side elevation similar to Fig. 2 but

with the leveling relay shown as when the elevator car is level with the corresponding floor.

Fig. 4 is also a side elevation similar to Fig. 2 but with the leveling relay shown as when the elevator car is approaching the corresponding floor.

Fig. 5 is a front elevation of the leveling relay and limit arms for a floor and with the same in positions also shown in Fig. 4 as when the elevator car is approaching the corresponding floor.

5 An elevator system according to the present invention is diagrammatically illustrated in Fig. 1 and may be installed in a structure 10 which is provided with a hatchway 11. A plurality of floors or landings 12a, 12b and 12c are spaced 15 along said hatchway 11 and a pair of hatchway doors 13 are mounted at each of said floors or landings.

The elevator car 14 is guided within said hatchway 11 in any suitable and conventional 20 manner. A cable drum 15 may be mounted above the hatchway 11 and may be encircled by a main cable 16 which has one end attached to the car 14 and the other end attached to a counterweight 17 moving in said hatchway 11 and counterbalancing said car 14. Said elevator car 14 may be raised and lowered by rotation of said cable drum 15 which is operated through any known type of connection, such as a gear train, by a suitable prime mover, such as an electric 30 motor 18. Said motor 18 is connected by a shaft 19, indicated by the broken line in Fig. 1, to a worm 20 which meshes with a worm wheel 21 in turn connected to a cable drum 15 by a shaft 22, also indicated by broken lines in Fig. 1. Although the invention is to be described with 35 respect to a traction type elevator drive from an electric motor to the elevator car, it is understood that the invention is equally applicable to all types of drives and prime movers now known 40 to the art.

The electric motor 18 is preferably of the three phase, two speed type and has a high speed winding 23 and a low speed winding 24. A three phase source of electric power is available 45 through the supply mains L1, L2 and L3. The motor circuits are conventional, are connected across said supply mains L1, L2 and L3, and are illustrated by heavy lines in Fig. 1.

The high speed motor circuits comprise a conductor 25 extending from supply main L1 to one leg of high speed winding 23 and including a pair of contacts 26 and a pair of contacts 27, a conductor 28 extending from supply main L2 to another leg of high speed winding 23 and 55

including a pair of contacts 29, and a conductor 30 extending from supply main L3 to the other leg of high speed winding 23 and including a pair of contacts 31. Said high speed winding 23 of the motor 18 is reversed by reversing the connections of supply mains L1 and L3 thereto. For this purpose, a conductor 32 extends from a point of conductor 25 to a point on conductor 30 and includes a pair of contacts 33, and a conductor 34, including a pair of contacts 35 extends from a point on conductor 30 to one of contacts 27 through which it is connected to conductor 25.

The low speed motor circuits comprise a conductor 36 which is connected through conductor 25 to supply main L1, which extends to one leg of low speed winding 24, and which includes a pair of contacts 37, comprise a conductor 38 which is connected through conductor 28 to supply main L2, which extends to another leg of low speed winding 24, and which includes a pair of contacts 39, and comprise a conductor 40 which is connected through conductor 30 to supply main L3, which extends to the other leg of low speed winding 24, and which includes a pair of contacts 41. Reversal of said low speed winding 24 may be accomplished through a conductor 42 which includes a pair of contacts 43 and which is between conductors 36 and 40 to connect the last mentioned leg of said low speed winding 24 to supply main L1, through a conductor 44 which includes a pair of contacts 45 and which is between said conductors 36 and 40 to connect the first mentioned leg of low speed winding 24 to supply main L3, and through a conductor 46 which includes a pair of contacts 47 and which bridges a portion of conductor 38 to connect the middle leg of low speed winding 24 to supply main L2.

The motor control circuits may be connected between supply mains L1 and L2 and include a car switch 48 including a pair of up terminals 49 and 50 and including a pair of down terminals 51 and 52. Wires 53 and 54, respectively, connect terminals 49 and 51 to supply main L1, while a wire 55 connects up terminal 50 to supply main L2 and a wire 56 connects down terminal 52 to supply main L2. A wire 57 is connected to supply main L2, has a branch 58 which includes a pair of contacts 59 and which is connected to wire 55, and has a branch 60 which includes a pair of contacts 61 and which is connected to wire 56.

An up contactor 62 includes a coil 63 which is in series with wire 55 and includes a rod 64 which is operated by said coil 63 and which carries a contact arm 65 for bridging contacts 59, a contact arm 66 for bridging contacts 26, and a contact arm 67 for bridging contacts 31. A down contactor 68 includes a coil 69 which is in series with wire 56 and includes a rod 70 which is operated by said coil 69 and which carries a contact arm 71 for bridging contacts 61, a contact arm 72 for bridging contacts 35, and a contact arm 73 for bridging contacts 33.

The motor control circuits for the low speed operation of the elevator car 14 include a bus wire 74 which is the only connection between supply main L2 and said low speed motor control circuits and which includes a pair of contacts 75. A high speed control contactor 76 includes a coil 77 which is in series with wire 57, includes an armature 78 operated by said coil 77, includes a rod 79 which is attached to said armature 78 and which carries a contact arm 80 for closing contacts 29 and a contact arm 81 for closing contacts

27, and includes a rod 82 also attached to armature 78 and carrying a contact arm 83 for closing contacts 75. A spring 84 is connected to said contact arm 83 normally to hold the same in closed position and said contact arms 80 and 81 in open positions.

An up leveling contactor 85 comprises a coil 86, an armature 87, and a rod 88 carrying a contact arm 89 for closing contacts 39, a contact arm 90 for closing contacts 41, and a contact arm 91 for closing contacts 37. A down leveling contactor 92 comprises a coil 93, an armature 94, and a rod 95 carrying a contact arm 96 for closing contacts 41, a contact arm 97 for closing contacts 45, and a contact arm 98 for closing contacts 43. Said leveling contactors 85 and 92 are of a well known type with armatures 87 and 94 both normally biased to open positions but adapted to be moved to closed positions upon energization of the respective coils 86 and 93.

The energization of said up and down leveling contactors 85 and 92 is supervised by a plurality of control circuits and by a plurality of leveling relays 99, each of which 99a, 99b and 99c corresponds to each of floors 12a, 12b and 12c in the hatchway 11. The particular construction of such leveling relays 99 will next be described in connection with Figs. 2-5 inclusive.

Each leveling relay 99 comprises a base member 100 to which is attached a bracket 101 and a magnetic coil 102. Said bracket 101 has a pair of journals 103. An armature 104 includes an arm 105 which is pivoted between said journals 103 by a pin 106 and includes a contact support 107 which is fastened to arm 105 and which carries two motor control contacts 108 and 109.

The motor control contact 108, see Figs. 2, 3 and 4, is mounted on a stem 110 which has a threaded end passing freely through contact support 107 and carrying an adjustable nut 111. A coil spring 112 encircles stem 110 and normally urges contact 108 to an extended position with nut 111 against said support 107, which extended position of motor control contact 108 may be varied by adjustment of nut 111. Contact 109 is also resiliently and adjustably supported in an identical manner by a stem 113 and nut 114, see Fig. 5.

Armature 104 includes abutments 115 which comprise a T-shaped arm 116 fastened to arm 105 and carrying a pair of adjustable thumb screws 117 and 118. Said armature 104 and abutments 115 are normally in the position shown in Fig. 2.

A pair of bearings 119 and 120 are mounted on said base member 100, a contact arm 121 is journaled on bearing 119 by a pin 122, and a contact arm 123 is journaled on bearing 120 by a pin 124. A motor control contact 125 is mounted upon the upper end of contact arm 121 by a stem 126 which is threaded into said contact arm 121 and locked in an adjusted position by nut 127. A motor control contact 128 is mounted upon the upper end of contact arm 123 by a stem 129 which is threaded into said contact arm 123 and locked in its adjusted position by a nut 130, see Fig. 4.

The lower end of contact arm 121 has a portion 131 which is provided with a bifurcated end for supporting the axle 132 of a roller 133 while a roller 134 is similarly supported upon the lower end of portion 135 of contact arm 123, see Fig. 4. The contact arms 121 and 123 are so proportioned and balanced upon their respective bearings 119 and 120 that both of said contact arms 121 and 123 have a normal tendency to rotate in a clock-wise direction. Stops are respectively provided to limit this normal movement of the 75

contact arms 121 and 123 and may each comprise a thumb screw 136 extending through base member 100 and adjustably fastened thereto by nuts 137. Similarly stops are also respectively provided to limit the rotation of the contact arms 121 and 123 in a counter-clockwise direction and may each comprise a thumb screw 138 extending through base member 100 and adjustably fastened thereto by nuts 139.

10 Resilient members are mounted between said armature 104 and the respective contact arms 121 and 123 normally to separate the contacts thereon. For instance, a leaf spring 140 may be fastened on contact support 107 opposite contact arm 121 so as not to engage the same when the magnetic coil 102 is not energized, see Fig. 2, but adapted to bear on said contact arm 121 and tending to separate motor control contacts 108 and 125 as shown in Fig. 3 when the magnetic 15 coil 102 is energized. A second leaf spring 141 may also be fastened to contact support 107 opposite contact arm 123 and tends to separate motor control contacts 109 and 128 upon energization of said coil 102, see Fig. 5.

20 As before mentioned there are leveling relays 99a, 99b, and 99c corresponding to each of the floors 12a, 12b, and 12c. Only the essential elements of said leveling relays 99a, 99b, and 99c are shown in the diagrammatic illustration of Fig. 1 and each element shown therein is designated by the general reference numeral and an alphabetical character corresponding to the floor 12a, 12b or 12c at which the relay controls leveling.

25 A mechanical control means operated by the elevator car 14 supervises the energization of the magnetic coil 102 of the leveling relay 99 as well as the positions of contact arms 121 and 123 as said car 14 approaches or stops at a floor or landing.

30 Such a mechanical control means includes a control drum 142 mounted above the hatchway 11 and encircled by a control cable 143 which is fastened to the car 14 by a bracket 144 and which is maintained under tension by a pulley 145 and a weight 146, see Fig. 1. A shaft 147 is journaled in bearing 148 and is attached to one end of control drum 142. A gear 149 on shaft 147 meshes with a gear 150 on a shaft 151 which is journaled in bearings 152. The ratio between gears 149 and 150 is selected so that shaft 151 makes less than one complete revolution, or turns through about 340°, during travel of the elevator car 14 along the entire height of the hatchway 11. A plurality of zone arms 153 are mounted in angular relation upon said shaft 151 and are each adjustable upon said shaft 151 by means of set screws 154. Each zone arm 153a, 153b and 153c, see Fig. 1, corresponds to each floor 12a, 12b and 12c.

35 Said mechanical control means also includes a shaft 155 journaled in bearings 156 and attached to the other end of control drum 142. A plurality of pairs of limit arms 157 and 158 are adjustably fastened to shaft 155 by representative set screws 159 and 160, see Fig. 5. An arcuate sector 161 is mounted upon the end of limit arm 157 and an arcuate sector 162 is mounted upon the end of limit arm 158. Said limit arms 157 and 158 are angularly displaced with respect to each other so that a gap is provided between the adjacent ends of said arcuate sectors 161 and 162, see Figs. 2, 3 and 4. Said limit arms 157 and 158 are also spaced longitudinally of said shaft 155 so that the arcuate sector 161 on limit arm 157

may engage the roller 133 on contact arm 121, see Fig. 4, while the other contact arm 123 assumes its normal position abutting against the respective thumb screw 136, or alternatively arcuate sector 162 on limit arm 158 may engage the 5 roller 134 on contact arm 123. Furthermore, said limit arms 157 and 158 are also adjusted on shaft 155 so that when car 14 is exactly level with the floor 12, the gap between said arcuate sectors will be opposite said rollers 133 and 134 so that 10 both contact arms 121 and 123 will rest against the thumb screws 136 as shown in Fig. 3.

15 The radial extent of limit arms 157 and 158 and arcuate sectors 161 and 162 may be greater than, equal to, or less than the radius of control drum 142. As will be readily understood, the accuracy of the leveling operation is increased when the radial extent of said limit arms is greater than the radius of drum 142 because the extremities of said limit arms 157 and 158 are then 20 moving faster than car speed and the movement of the car 14 is magnified at the ends of said longer limit arms so that said rollers 133 and 134 are disengaged more consistently at a time when the car 14 is in the same position in the 25 hatchway 11.

As illustrated herein, the limit arms 157 and 158 rotate in a clockwise direction when the car 14 is moving upwardly and in a counter-clockwise direction when car 14 is moving downwardly, 30 see arrows in Figs. 2, 3 and 4. Also the zone arm 153 is indicated by the arrows as rotating in a counter-clockwise direction when the car is moving upwardly. However, it is to be understood that said arms may rotate in either direction as long as their relative timing meets the conditions later to be set forth.

35 A plurality of pairs of limit arms 157a and 158a, 157b and 158b, and 157c and 158c are provided on shaft 155 and each pair corresponds to 40 one of the floors 12a, 12b and 12c, see Fig. 1. It is obvious that when the magnetic coil 102 of each leveling relay 99 is not energized that the contact arms 121 and 123 on each relay 99 are maintained in the positions illustrated in Fig. 2 45 by the abutments 115 on armature 104 so that there is ample clearance between rollers 133 and 134 and the arcuate sectors 161 and 162 on the limit arms 157 and 158, otherwise the thumb screws and/or 118 on said armature 104 are adjusted so that there is sufficient clearance between said rollers 133 and 134 and said sectors 161 and 162.

50 Upon energization of the magnetic coil 102, the attraction of armature 104 frees said contact arms 121 and 123 so that the rollers 133 and 134 thereon move into the paths of the sectors 161 and 162 on limit arms 157 and 158 but such energization of the magnetic coils 102a, 102b and 102c 55 is selectively controlled and takes place only when the elevator car 14 is near the corresponding floor 12a, 12b or 12c in a manner next to be described.

55 The energizing circuit for each magnetic coil 102 includes a pair of zone contacts 163 and 164 60 which are normally open, contact 164 being operated by an actuating rod 165. Said actuating rod 165 is positioned so as to be operated by the zone arm 153 whereupon said contacts 163 and 164 are closed, see Figs. 3 and 4. The zone arm 153 65 is designed and angularly adjusted on shaft 151 so that said contacts 163 and 164 are closed only when the elevator car 14 is in the vicinity of the floor 12 corresponding to the particular set of contacts 163 and 164 and zone arm 153. Contact 70 75

163 is connected to one side of magnetic coil 102 by a wire 166.

The several control circuits are connected to supply main L1 by a bus wire 167, see Fig. 1.

- 5 The energizing circuit for leveling relay 99a comprises a wire 168a extending from bus wire 167 to zone contact 163a, a wire 166a extending from zone contact 164a to one side of magnetic coil 102a, and a wire 169a extending from the other side of magnetic coil 102a to bus wire 74. The energizing circuit for leveling relay 99b includes a wire 168b extending from bus wire 167 to zone contact 163b, a wire 166b extending from zone contact 164b to magnetic coil 102b, and a wire 169b extending from magnetic coil 102b to bus wire 74. The energizing circuit for leveling relay 99c includes a wire 168c extending from bus wire 167 to zone contact 163c, a wire 166c from zone contact 164c to magnetic coil 102c, and a wire 169c from magnetic coil 102c to bus wire 74.

The motor control contacts 108 and 109 on the armature 104 are each connected to bus wire 167, motor control contact 109a being connected to bus wire 167 by wire 170a, and motor control contact 108a being connected to bus wire 167 by a wire 171a. Wires 170b, 171b, 170c and 171c, respectively, connect motor control contacts 109b, 108b, 109c and 108c to said bus wire 167. The motor control contacts 128a, 128b and 128c on the contact arms 123a, 123b and 123c are respectively connected by wires 172a, 172b and 172c to a wire 173 which leads to one side of the coil 86 of up leveling contactor 85, the other side of said coil 86 being connected to bus wire 74 by a wire 174. The motor control contacts 125a, 125b and 125c on contact arms 121a, 121b and 121c are respectively connected by wires 175a, 175b and 175c to a wire 176 which extends to one side of coil 93 of the down leveling contactor 92, the other side of said coil 93 being connected to bus wire 74 by a wire 177.

There are two motor control circuits for each floor, one circuit being an up leveling control circuit and the other a down leveling control circuit. For instance the up leveling control circuit for floor 12a may be traced as follows: from supply main L1, wire 167, wire 170a, contacts 109a and 128a respectively on armature 104a and contact arm 123a of leveling relay 99a, wire 172a, wire 173, up leveling contactor coil 86, wire 174, bus wire 74, through contacts 75 and contact arm 83 to supply main L2. The down leveling control circuit for floor 12a is from supply main L1, wire 167, wire 171a, contacts 108a and 125a respectively on armature 104a and contact arm 123a of leveling relay 99a, wire 175a, wire 176, down leveling contactor coil 93, wire 177, bus wire 74, through contacts 75 and contact arm 83 to supply main L2. The up and down leveling motor control circuits for the other floors are similar to those just traced and it is pointed out that the motor control contacts are paired so that motor control contacts 109a and 128a, 108a and 125a, 109b and 128b, 108b and 125b, 109c and 128c, 108c and 125c, make or break contact with each other to close or open the respective motor control circuits.

The operation of the automatic elevator leveling system according to the present invention will now be described.

When the elevator car 14 is stopped at a floor, the contactors 62, 68, 76, 85 and 92 are all in their normally open positions and all motor control circuits and all motor circuits are open.

75 Fig. 1 illustrates another condition with up level-

ing contactor 85 in closed position which should not be confused with the conditions when the elevator is stopped at any particular floor.

Assume that the operator on the car 14 moves the car switch 48 upwardly. The up terminals 49 and 50 of said car switch 48 are bridged and up contactor 62 is placed across supply mains L1 and L2. Upon energization of up contactor 62, rod 64 is raised, contact arm 66 closes contacts 26, contact arm 67 closes contacts 31, and contact arm 65 closes contacts 59 so that coil 77 of high speed contactor 76 is energized. Such energization of said coil 77 moves rod 79 against the action of spring 84 so that contact arm 89 closes contacts 29 and contact arm 81 closes contacts 27. The three phase high speed winding 23 of the motor 18 is now fully energized and the car 14 will be raised at full speed.

At the same time energization of coil 77 has moved rod 82 to withdraw contact arm 83 from contacts 75 and since all other energizing or control circuits are fed through contacts 75 they can not now become operative during high speed operation of the car 14. For instance each time that car 14 approaches one of the floors 12a, 12b or 12c, the zone arms 153a, 153b or 153c close the contacts 163a and 164a, 163b and 164b, 163c and 164c, respectively, but since contacts 75 are open, none of the energizing circuits or magnetic coils 102 can be energized so that the leveling relays 99a, 99b and 99c maintain the position illustrated in Fig. 2 and the sectors 161 and 162 of limit arms 157 and 158 pass rollers 133 and 134 without engaging the same.

When the car is approaching a floor 12 at 35 which it is desired to stop, the operator moves the car switch 48 to the open position shown in Fig. 1. Assuming that the car has been moving upwardly toward floor 12a, see Fig. 1, the contactors 62 and 76 are opened and the high speed winding 23 of motor 18 is de-energized. At the same time, however, zone arm 153a has operated actuating rod 165a to close zone contacts 163a and 164a. Now since contactor 76 is de-energized contacts 75 are closed by contact arm 83 45 and magnetic coil 102a is energized through the energizing circuit, as previously traced, between supply mains L1 and L2. Furthermore, the arcuate sector 162a on limit arm 158a is now in position to engage the roller 134a on contact arm 123a, see Fig. 1, and hold the motor control contact 128a therein in position to make with the contact 109a on armature 104a which is now attracted by magnetic coil 102a. On the other hand, the arcuate sector 161a on limit arm 157a 55 is not opposite roller 133a so that contact arm 121a swings to inoperative position against the thumb screw 136 and motor control contacts 108a and 125a remain open.

Since motor control contacts 109a and 128a 60 are closed, the motor control circuit to up leveling contactor 85 is completed across supply mains L1 and L2 so that the coil 86 is energized and the rod 88 is operated to move contact arm 89 against contacts 39, contact arm 90 against contacts 41, and contact arm 91 against contacts 37. Closure of said contacts 37, 39 and 41 places the three phases of the low speed motor winding 24 across the three phase supply mains L1, L2 and L3 so that the elevator 14 continues to move upwardly but at low speed. Since contacts 108a and 125a are open, down leveling contactor 92 can not be energized. This condition of the zone arm 153a, zone contacts 163a and 164a being closed, blocking of contact arm 123a by limit arm 75

158a to close motor control contacts 109a and 128a upon energization of magnetic coil 102a and energization of up leveling contacting 85 to close the motor circuits to the low speed up winding 24 of the motor 18 is indicated in Fig. 1.

The elevator car is now moving upwardly at low speed. The arcuate sector 162a and limit arm 158a are so designed and located so that roller 134a is disengaged and contact arm 123a moves to its normal position under the action of spring 141 which also causes a quick break between motor control contacts 109a and 128a precisely when the platform of the elevator car 14 becomes even or level with the floor 12a. Opening of contacts 108a and 128a de-energizes upleveling contactor 85 to open contacts 37, 39 and 41 and de-energizes the motor winding 24 so that the car 14 is stopped. In case the opening of contacts 109a and 128a is not timed just right, the limit arm 158a may be angularly adjusted on shaft 155 to correct the time for opening of said contacts 109a and 128a or the adjustable mountings for contacts 109a or 128a may be adjusted by appropriate adjustment of nuts 114 or 130 to retract or project said contacts.

If the car switch 48 is moved downwardly to bridge the down terminals 51 and 52 thereof, down contactor 68 and high speed contactor 76 are energized and the high speed winding 23 of motor 18 is connected across supply mains L1, L2 and L3 in such phase relation that the motor 18 is reversed and the car 14 moves downwardly. At the same time contacts 75 are opened so that none of the leveling control circuits can be energized.

Opening of the car switch 48 as the car 14 is lowered toward a floor at which it is desired to stop will de-energize the high speed motor winding 23 and contacts 75 will be closed by the concurrent de-energization of high speed contactor 76. Assume that the car 14 is moving downwardly toward floor 12b, zone arm 153b will be in engagement with actuating rod 165b and zone contacts 163b and 164b will be closed to complete the energization circuit through magnetic coil 102b. Limit arm 157b is so located or timed that its arcuate sector 161b is now in position to engage roller 133b when armature 104b is energized and contact arm 121b is swung upwardly so that contacts 108b and 125b are closed. However, since the car 14 is moving downwardly roller 134b is not engaged by the sector 162b on limit arm 158b so that contacts 109b and 128b are open under these conditions which are illustrated in Fig. 4.

Since contacts 108b and 125b are closed, the motor control circuit to down leveling contactor 92 will be completed across supply mains L1 and L2 and the low speed down motor contacts 43, 45 and 47 will be closed by contact arms 98, 97 and 96, respectively, of said down leveling contactor 92. The car 14 is now moving downwardly at low speed and said arcuate sector 161b on limit arm 157b disengages roller 133b under the action of spring 140b to open motor control contacts 108b and 125b precisely so that down leveling contactor 92 is de-energized and said low speed down motor contacts 43, 45 and 47 are opened to stop said car 14 with its platform level with floor 12b. Again in case this timing is not quite accurate limit arm 157b may be angularly adjusted on shaft 155 or contacts 108b and 125a may be adjusted to correct the timing.

If, for any reason, such as slip in the brake or cable stretch, the car 14 should overshoot the

floor at which it is stopping the other roller will ride up on the arcuate sector of the other limit arm and the motor control contacts for moving the car in the opposite direction will be closed. Specifically, if such over shooting took place during the down leveling at floor 12b as just described, roller 134b would ride up on arcuate sector 162b so that contact arm 123b would be moved to close motor control contacts 109b and 128b. It should be noted that the limit arms 157 and 158 are moved independently of the main cable 16 for the car 14 so that stretching thereof does not affect the proper timing or positioning of said limit arms. Since the up motor control contacts 109b and 128b are closed by such downward overshooting, up leveling contactor 85 is energized and the car moves upwardly at low speed but now under the control of limit arm 162b. The cessation of this return movement is then controlled as previously explained with respect to the up leveling conditions.

It should also be noted that zone contacts 163 and 164 are always closed by zone arm 153 when the car is at or near the corresponding floor 12 and irrespective of whether the car 14 is moving or is stopped. Hence if for any reason the car 14 should raise or drop after having come to a stop level with the floor, the corresponding leveling relay 99 remains energized and the proper roller 133 or 134 rides up on the corresponding sector 161 or 162 so that the leveling operations are repeated to re-level the car with respect to the floor. The extreme normal positions of rollers 133 and 134 are predetermined by the adjustment of thumb screws 136 so that said rollers 133 and 134 will ride up on said sectors 161 and 162 during the re-leveling functions of the leveling relay 99.

The zone arms 153 and limit arms 157 and 158 are preferably timed with respect to each other so that the magnetic coil 102 of the leveling relay is not energized at least until the leading edge of the arcuate sectors 161 and 162 are in position to engage either roller 133 or 134 respectively. This condition is assured because the zone arms 153 move through a relatively small angle since they are operated through reduction gears 149 and 150 while limit arms 157 and 158 are moving at greater than car speed and travel through a relatively large angle.

One outstanding feature of the automatic elevator leveling system of the present invention is that the leveling relays 99, zone arms 153 and limit arms 157 and 158 may all be located at one place such as in the pent-house or motor room above the elevator hatchway. Hence it is a simple matter to make any of the necessary adjustments to control the operation and accurate leveling of the car. Such adjustments, as have been previously explained, may be angular adjustment of the zone arms 153 upon shaft 151 by means of set screws 154, may be angular adjustment of limit arms 157 and 158 upon shaft 155 by means of set screws 159 and 160, respectively, to alter the timing of said limit arms 157 and 158 with respect to said zone arms 153 and of the arcuate sectors 161 and 162 on limit arms 157 and 158 with respect to said rollers 133 and 134, respectively, or may be leveling relay adjustments such as adjustment of the motor control contacts 108 and 109 by means of nuts 111 and 114 and motor control contacts 125 and 128 by means of nuts 127 and 130 for fine adjustment of the timing of the motor control contacts, such as adjustment of the thumb screws 117, 118, 136 75

and 138 to vary the extreme positions of the contact arms 121 and 123 for clearance between sectors 161 and 162 and rollers 133 and 134, see Fig. 2, and for adjustent of the normal inoperative positions of said contact arms 121 and 123, see Fig. 3.

Although the high speed motor control circuits are completed and opened by the car switch 48, it is obvious that other types of motor control switches, such as push buttons, may be used at the floors or on the cars. It is also understood that standard equipment such as brakes, gate switches, interlocks, etc., will in general be used with the leveling system of the invention but such equipment has not been illustrated or described because the provision and application thereof will be realized by those skilled in the art.

Since many variations of the invention are possible, the present disclosure and description are to be construed in an illustrative sense, the scope of said invention being defined in the appended claims.

Having now particularly described my invention, what I desire to secure by Letters Patent of the United States and what I claim is:

1. In an automatic system for leveling an elevator car with respect to a floor, the combination with a prime mover connected to said elevator car and for moving the same with respect to said floor, controlling means associated with said prime mover for controlling the operation thereof, a control circuit including a control coil for operating said controlling means and including a pair of control contacts, and a leveling relay including an armature carrying one of said control contacts, including a contact arm carrying the other control contact, and including a magnetic coil adapted upon being energized to attract and hold said armature in position for engagement of the control contact thereon with the control contact on said contact arm, of an energizing circuit including zone contacts and said magnetic coil, a zone arm connected to said car and adapted to close said zone contacts for energization of said magnetic coil only when said car is near said floor, and a limit arm connected to and having a movement corresponding to the movement of said car, for engaging said contact arm to hold it and the control contact thereon in position for contact with the control contact on said armature upon energization of said magnetic coil, and disengaging said contact arm to open said contacts and said control circuit so that said controlling means is operated to stop said prime mover precisely when the car is level with said floor.

2. In an automatic system for leveling an elevator car with respect to a floor, the combination with a motor connected to said elevator car and for moving the same with respect to said floor, a motor circuit including motor contacts and said motor, a motor control circuit including a contactor for operating said motor contacts and including a pair of motor control contacts, and a leveling relay including an armature carrying one of said motor control contacts, a contact arm carrying the other motor control contact, and including a magnetic coil adapted upon being energized to attract and hold said armature in position for engagement of the control contact thereon with the control contact on said contact arm, of an energizing circuit including zone contacts and said magnetic coil, a zone arm connected to said car and adapted to close said zone contacts for energization of said coil only

when said car is near said floor, and a limit arm connected to and having a movement corresponding to the movement of said car, for engaging said contact arm to hold the motor control contact thereon in position for contact with the other motor control contact upon energization of said coil, and adapted to disengage said contact arm and permit separation of said control contacts.

3. In an automatic system for leveling an elevator car with respect to a floor, the combination with a motor connected to said elevator car and for moving the same with respect to said floor, a motor circuit including motor contacts and said motor, a motor control circuit including a contactor for operating said motor contacts and including a pair of motor control contacts and a leveling relay including an armature carrying one of said motor control contacts and normally in an inoperative position, a magnetic coil adapted upon being energized to move said armature to an operative position, and a contact arm carrying the other motor control contact and normally in an inoperative position irrespective of the energization of said magnetic coil, of an energizing circuit including zone contacts and said magnetic coil, a zone arm connected to said car and for closing said zone contacts to energize said magnetic coil and attract said armature only when said car is near said floor, and a limit arm connected to said car to move at a speed corresponding to car speed and for maintaining said contact arm in operative position as said car approaches said floor whereby said motor contacts are closed.

4. In an automatic system for leveling an elevator car with respect to a floor, the combination with a motor connected to said elevator car and for moving the same with respect to said floor, a motor circuit including motor contacts and said motor, a motor control circuit including a contactor for operating said motor contacts and including a pair of motor control contacts, and a leveling relay including an armature carrying one of said motor control contacts, having an abutment and normally in an inoperative position, a magnetic coil adapted upon being energized to move said armature to operative position, and a contact arm carrying the other motor control contact and normally in an inoperative position irrespective of the energization of said magnetic coil, of an energizing circuit including zone contacts and said magnetic coil, a zone arm connected to said car and for closing said zone contacts to energize said magnetic coil and attract said armature to operative position only when said car is near said floor, and a limit arm connected to said car to move at a speed corresponding to car speed and for maintaining said contact arm in operative position as said car approaches said floor, said abutment on the armature engaging said contact arm normally to maintain the same out of the path of said limit arm when said magnetic coil is not energized.

5. In an automatic system for leveling elevators, the combination with an elevator assembly including a hatchway having a plurality of floors, an elevator car movable within said hatchway, and a prime mover connected to said elevator car and for moving the same with respect to said floor, controlling means associated with said prime mover for controlling the operation thereof, a control circuit including a control coil for operating said controlling means and including a plurality of pairs of control contacts, each corre-

sponding to one of said floors, and a plurality of leveling relays each corresponding to one of said floors and to one pair of control contacts and each including an armature carrying one of the respective pair of control contacts, a contact arm carrying the other control contact of said pair, and each including a magnetic coil adapted upon being energized to attract and hold said armature in position for engagement of the control contact thereon with the control contact on said contact arm, of a plurality of energizing circuits each including a pair of zone contacts and the magnetic coil of one of said leveling relays, a plurality of zone arms connected to said car and each adapted to close the corresponding zone contacts for energization of the respective magnetic coil only when said car is near the corresponding floor, and a plurality of limit arms all connected to said car to move at a speed corresponding to car speed, each for engaging the corresponding contact arm of the respective leveling relay to hold it and the contact thereon in position for contact with the control contact on the associated armature upon energization of the corresponding magnetic coil, and each disengaging the corresponding contact arm precisely when the car is level with the respective floor to permit disengagement of the control contacts on the energized leveling relay.

6. In an electro-mechanical automatic system for leveling an elevator car with respect to a floor, the combination with a motor connected to said elevator car and for moving the same with respect to said floor, and a leveling relay for each floor and including a pair of normally open motor control contacts, a contact arm carrying one of said motor control contacts, an armature carrying the other of said motor control contacts, and a magnetic coil for attracting said armature to close said motor contact, of an energizing circuit connected to said magnetic coil and including a pair of zone contacts, and a mechanical control means connected to said elevator car, including a zone arm for closing said zone contacts only when said car is adjacent to said floor to energize said coil and close said motor control contacts, and including a limit arm moving at a speed corresponding to car speed for engaging said contact arm to maintain said motor contacts closed as the car approaches said floor and for permitting said motor contacts to open just as the car becomes level with said floor.

7. In an automatic leveling system for elevators, the combination with an elevator car within a hatchway having a plurality of landings, a motor connected to said elevator car and for moving the same within said hatchway, a leveling relay for each landing and including two pairs of control contacts, two contact arms each carrying one contact of each pair of control contacts, a magnetic coil, and an armature carrying the other contact of each pair of control contacts, a mechanical control means connected to said elevator car, including a set of zone arms rotating only once for each passage of said car through said hatchway, and including a set of pairs of limit arms rotating at a speed corresponding to car speed, an energizing circuit connected to the magnetic coil of each leveling relay and including a pair of zone contacts which are closed by the corresponding zone arm as the car approaches a landing, and a motor control circuit including said control contacts which are opened by the appropriate limit arm when a car is level with the landing.

3. In a leveling system for elevators, the combination with an elevator car within a hatchway with a plurality of landings, a reversible motor connected to said elevator car and for moving the same within said hatchway, and a leveling relay 5 for each landing and including two pairs of normally opened motor control contacts, a pair of contact arms each carrying one of each pair of said motor control contacts, a single armature carrying both of the other of said pair of motor control contacts, and a magnetic coil for attracting said armature to close said motor control contacts, of a plurality of holding circuits each connected to the magnetic coil of each leveling relay and including a pair of zone contacts, an up 10 motor control circuit including one pair of motor control contacts on said leveling relay, a down motor control circuit including the other pair of motor control contacts on said leveling relay, and a mechanical control means connected to said elevator car, including a zone arm for closing said zone contacts only when said car is adjacent to the corresponding landing to energize said magnetic coil and attract said armature, and including a pair of limit arms moving at a speed 15 corresponding to car speed and each for engaging one of said contact arms alternatively, one of said limit arms engaging the contact arm carrying one of the motor control contacts in the up motor control circuit to maintain said contacts closed 20 while the car is moving upwardly toward said landing, and the other of said limit arms engaging the other contact arm carrying one of the motor control contacts in the down motor control circuit to maintain said contact closed while the 25 car is moving downwardly to said landing, neither of said limit arms engaging the respective contact arms when the car is level with the landing in which position both pairs of contacts are normally open.

9. In a leveling assembly for an elevator car, the combination with a limit arm having the end thereof moving with the elevator car and through a distance corresponding to the travel of said car, of a leveling relay comprising a contact arm 40 movably mounted and located normally to assume a position in the path of and adapted to bear against said limit arm, an armature movably mounted normally to assume an inoperative position, an abutment adjustably connected 45 to said armature and adapted during inoperative position of said armature to engage said contact arm and hold it out of the path of said limit arm, and a magnetic coil positioned and adapted upon being energized to move said armature into 50 operative position and for disengagement of said abutment and said contact arm so that said contact arm may move into the path of said limit arm.

10. In a leveling assembly for an elevator car, 60 the combination with a limit arm having the end thereof moving with the elevator car and through a distance corresponding to the travel of said car, of a leveling relay comprising a base member, a contact arm movably mounted thereon 65 and located normally to assume a position in the path of and adapted to bear against said limit arm, a stop on said base member and for limiting the normal movement of said contact arm into the path of said limit arm, an armature 70 movably mounted on said base member normally to assume an inoperative position and engaging said contact arm to hold it out of the path of said limit arm, and a magnetic coil positioned and adapted upon being energized to move said 75

armature into operative position, in which position said contact arm is free normally to move into the path of said limit arm and into engagement with said stop which determines the ultimate position of said contact arm.

11. In a leveling assembly for an elevator car, the combination with a limit arm having the end thereof moving with the elevator car and through a distance corresponding to the travel of said car, of a leveling relay comprising a base member, a contact arm movably mounted thereon and located normally to assume a position in the path of and adapted to bear against said limit arm, an armature movably mounted on said base member normally to assume an inoperative position and having an abutment engaging said contact arm to hold it out of the path of said limit arm, and a stop on said base member for engaging said contact arm to limit the movement of said contact arm out of the path of said limit arm by the abutment on said armature.

12. In a leveling assembly for an elevator car, the combination with a limit arm having the end thereof moving with the elevator car and through a distance corresponding to the movement of said elevator car, of a leveling relay comprising a contact arm movably mounted and located normally to assume a position with a portion of said contact arm in the path of and adapted to bear against the end of said limit arm, a contact on said contact arm, an armature movably mounted to assume an inoperative position, a second contact adjustably mounted on said armature and for engaging said contact on the aforementioned contact arm, and a magnetic coil positioned and adapted upon being energized to move said armature and adjustable contact toward said contact arm for closure of said contacts at a time determined by the adjustment of said adjustable contact.

13. In an automatic system for leveling an elevator car with respect to a floor, the combination with a pair of limit arms having the ends thereof moving with the elevator car and through a distance corresponding to the movement of said elevator car, of a leveling relay comprising a pair of contact arms movably mounted and each located normally to assume a position with a portion thereof in the path of and to bear against the end of the respective limit arm, a contact on each of said contact arms, an armature movably mounted normally to assume an inoperative position and having a pair of parts for engaging respective contact arms and adapted to hold each contact arm out of engagement with the respective limit arm, a pair of contacts on said armature, and a magnetic coil positioned and adapted upon being energized to move said armature toward said contact arm, said limit arms being relatively displaced, one of said limit arms engaging one contact arm when the elevator car is above said floor for closure of the corresponding contact on the armature and said one contact arm, and the other of said limit arms engaging the other of said contact arms when the elevator car is below said floor for closure of the corresponding contact on the armature and said other contact arm.

14. In an automatic system for leveling an elevator car with respect to a floor, the combination with a pair of limit arms having their ends angularly displaced and rotating through a distance corresponding to the travel of said car, of a leveling relay comprising a pair of contact arms

movably mounted and located normally to assume a position with each contact arm in the path of and adapted to bear against one of said limit arms, a contact on each contact arm, an armature movably mounted, adapted normally to assume an inoperative position and for holding said contact arm out of the path of the respective limit arm, a pair of contacts on said armature, and a magnetic coil positioned and adapted upon being energized to move said armature toward said contact arm and releasing said contact arm to permit normal movement thereof, one of said limit arms engaging one of said contact arms when said elevator car is above said floor to hold said one contact arm in position for closure of the corresponding contact on the armature and the engaged contact arm upon energization of said coil, the other of said limit arms alternatively engaging the other of said contact arms when said elevator car is below said floor to hold the other said contact arm in position for closure of the corresponding contact on the armature and the engaged contact arm during energization of said coil, and neither of said limit arms being opposite said contact arms when the elevator car is level with said floor to permit both of said contact arms to move to normal inoperative positions to open simultaneously in spite of the energization of said coil.

15. In a leveling assembly for an elevator car, the combination with a limit arm having the end thereof moving with the elevator car and through a distance corresponding to the movement of said elevator car, of a leveling relay comprising a contact arm movably mounted and located normally to assume a position with a portion of said contact arm in the path and adapted to bear against the end of said limit arm, a contact on said contact arm, an armature movably mounted normally to assume an inoperative position and having a part for engaging said contact arm to hold the same out of engagement with said limit arm, a second contact on said armature, and a magnetic coil positioned and adapted upon being energized to move said armature toward said contact arm for closure of the contacts thereon as long as said contact arm bears against said limit arm, said contacts being separated upon disengagement of said contact arm and said limit arm even though said magnetic coil is energized.

16. In a leveling assembly for an elevator car, the combination with a limit arm having the end thereof moving with the elevator car and through a distance corresponding to the travel of said car, of a leveling relay comprising a contact arm movably mounted and located normally to assume a position in the path of and adapted to bear against the end of said limit arm, a contact on said contact arm, an armature movably mounted normally to assume an inoperative position and for engaging said contact arm to hold the same out of the path of said limit arm, a second contact on said armature, a magnetic coil positioned and adapted upon being energized to move said armature toward said contact arm for closure of the contacts thereon during engagement of said contact arm and said limit arm, and a resilient means between said armature and said contact arm, tending to separate said arms and causing separation of said contacts immediately upon disengagement of said contact arm and said limit arm.

17. In a leveling system for an elevator car moving with respect to a landing, the combination with a shaft connected to said elevator car,

- a limit arm on said shaft and having its end moving through a distance corresponding to the travel of said elevator car, and an adjustable connection between said shaft and said limit arm,
- 5 of a leveling relay comprising a contact arm movably mounted and located normally to assume a position with said contact arm in the path of and adapted to bear against said limit arm, a contact on said contact arm, an armature movably mounted and adapted normally to assume an inoperative position and having a part for engaging said contact arm to hold the same out of engagement with said limit arm, a second contact upon said armature, and a magnetic coil positioned and adapted upon being energized to move said armature toward said contact arm for closure of the contacts thereon during engagement of said contact arm and said limit arm, said contacts being separated, even though said coil
- 10 is energized, upon disengagement of said contact arm and said limit arm, the moment of said disengagement being variable to take place precisely when the car is level with said landing by adjustment of the limit arm with respect to said shaft.
- 15 18. In an electro-mechanical relay, the combination with a base, an electro-magnetic coil mounted upon said base, an armature pivoted on said base normally to swing away from said coil but adapted to be attracted toward said coil upon energization thereof, a contact arm carrying a contact on one end and a roller on the other end thereof and intermediately pivoted to said base, a pair of stops adjustably mounted upon said base, one to limit the rotation of said contact arm in one direction and the other to limit the rotation of said contact arm in the opposite
- 20 direction, a second contact adjustably mounted upon said armature and positioned so as to engage the contact on said contact arm when said coil is energized, an abutment adjustably mounted on said armature and for engaging said contact arm to hold the same against one of said stops during normal position of said armature, a spring arm between said armature and said contact arm and for normally separating the contacts thereon but adapted to be overcome for engagement of 10 said contacts upon energization of said electromagnetic coil, and a limit arm for engaging the roller on said contact arm to hold the contact on said contact arm in position for engagement with the other contact upon energization of said coil. 15
- 25 19. In an electro-mechanical relay, the combination with a support, a contact arm carrying a contact and movable to a contacting position, a magnetic arm also carrying a contact, normally in an inoperative position and movable to an energized position, a resilient means between said magnetic arm and said contact arm for separating the same and the contacts thereon, a control member for engaging said contact arm and moving the same to contacting position, and a 25 coil adjacent said magnetic arm and adapted upon being energized to move said magnetic arm to energized position and to move the contact thereon into contact with the contact on said contact arm, said resilient means being adapted upon 30 disengagement of said control member and said contact arm to separate the contacts on said magnetic and control arms even though said coil is still energized.

JAMES H. BARTHOLOMEW. 35
